[57] CLAIM

The ornamental design for a ventilated cat litter box, as shown and described.

DESCRIPTION

FIG. 1 is a top, front and right side perspective view of a ventilated cat litter box showing my design;
FIG. 2 is a front elevational view thereof;
FIG. 3 is a right side elevational view thereof;
FIG. 4 is a left side elevational view thereof;
FIG. 5 is a rear elevational view thereof;
FIG. 6 is a top plan view thereof, the bottom being unadorned; and,
FIG. 7 is another perspective view thereof with part of the roof and front wall broken away for purposes of illustration.

FIG. 1.

FIG. 2.

FIG. 3.

FIG. 4.

FIG. 5.

FIG. 6.

FIG. 7.
